SPECTACLE FRAME OR THE LIKE

Ralph J. T. Bauer, Southbridge, Mass., assignor
to American Optical Company, Southbridge,
Mass., a voluntary association of Massachusetts

Application February 12, 1953, Serial No. 23,575

Term of patent 14 years

(Cl. D57—1)

To all whom it may concern:

Be it known that I, Ralph J. T. Bauer, a citizen of the United States of America, residing at Southbridge, in the county of Worcester and State of Massachusetts, have invented a new, original, and ornamental Design for a Spectacle Frame or the like, of which the following is a specification, reference being made to the accompanying drawings, forming a part thereof.

Fig. 1 is a perspective view of a spectacle frame showing my new design;

Fig. 2 is a fragmentary top plan view thereof, the temples being partly broken away for convenience of the illustration; and

Fig. 3 is a side elevational view thereof.

The dominant features of my design reside in

the portions shown in full lines in the drawing.

I claim:

The ornamental design for a spectacle frame or the like, substantially as shown and described.

RALPH J. T. BAUER.
